(57) **CLAIM**

The ornamental design for a housing for a communication device or similar articles, as shown.

DESCRIPTION

FIG. 1 is a front elevation view.

FIG. 2 is a rear elevation view of the view.

FIG. 3 is a first side elevation view.

FIG. 4 is a second side elevation view.

FIG. 5 is a top plan view.

FIG. 6 is a bottom plan view; and,

FIG. 7 is a front, side and top perspective view of the ornamental design for a housing for a communication device or similar articles.

The broken line showings throughout the views are for illustrative purposes only and form no part of the claimed design.
